STEREOPHONIC HEAD SET

Bernard Kantor, South Farmingdale, N.Y., assignor to
Stanton Magnetics, Inc., Plainview, N.Y.

Filed Aug. 24, 1970, Ser. No. 24,655

Term of patent 14 years

Int. Cl. D14—01

U.S. Cl. D26—14

FIG. 1

FIG. 2

FIG. 1 is a perspective view of the stereophonic head set showing my new design; and

FIG. 2 is an end elevational view of the stereophonic head set of FIG. 1.

I claim:

The ornamental design for a stereophonic head set, as shown.
